CIGARETTE POCKET

Albert T. Bard, Chicago, Ill., and Alvin J. Wenzel, Michigan City, Ind.; assignors to Reliance Manufacturing Company, Chicago, Ill., a corporation of Illinois

Application September 16, 1942, Serial No. 458,538

1 Claim. (Cl. 2—247)

Our invention relates generally to cigarette pockets and more particularly to cigarette pockets for work shirts and other articles of wearing apparel.

It is an object of our invention to provide a durable cigarette pocket which may be fabricated from a minimum amount of material.

A further object is to provide a cigarette pocket which is spacious without the use of extra cloth.

Another object is to provide a cigarette pocket having an improved closure and an improved bottom construction which cooperate to facilitate the removal of either a single cigarette or an entire package of cigarettes.

Another object of our invention is to provide a unitary cigarette pocket with an improved flap construction which permits easy removal of either a single cigarette or the entire package of cigarettes.

A still further object is the provision of a pocket which is simple in design and economical to manufacture.

Other objects and advantages will appear from the following description.

In the drawings:

Fig. 1 is a front view partially broken away, showing a shirt embodying our novel pocket;

Fig. 2 is a view similar to Fig. 1, showing the manner by which a single cigarette is removed from the pocket;

Fig. 3 is a vertical, sectional view taken on the line 3—3 of Fig. 1;

Fig. 4 is a view showing a horizontal section taken on the line 4—4 of Fig. 1;

Fig. 5 is a view of a vertical section taken on the line 5—5 of Fig. 3, showing the cigarette pocket unbuttoned and empty;

Fig. 6 is a plan view of the blank from which the pocket is formed;

Fig. 7 is a plan view of the flap reinforcement; and

Fig. 8 is a fragmentary perspective view broken away to show the lower corner construction of our pocket.

Referring to the drawings, it will be seen that we have illustrated an embodiment of our invention wherein the new and improved cigarette pocket comprises a pocket element 10 and a reinforcing element secured by suitable stitching to each other and to the front of a work shirt 14. The pocket element is originally cut in the form of the blank shown in Fig. 6 and has straight parallel sides 16 and 18, a straight bottom 20 perpendicular to the sides and a tapered top having inclined edges 22 and 24 meeting at a cen-

trally located apex 26. The sides and top edges of the pocket element 10 are folded back upon themselves along the dot dash lines 28, 30, 32 and 34 to provide side hems 36 and 38 (Fig. 4) and a tapered top hem 40 (Figs. 3 and 5).

The reinforcing element 12 is cut to the shape shown in Fig. 7 and generally conforms to the shape of the pocket element 10, except that the reinforcing element 12 is much shorter than the pocket element. This reinforcing element is of the same width as the pocket element and has parallel sides 42 and 44, a straight bottom 46 perpendicular to the sides 42 and 44 and a tapered top having inclined edges 48 and 50 meeting at the apex 52. The inclination of the edges 48 and 50 is the same as that of the edges 22 and 24 of the pocket element 10.

The side edges of the reinforcing blank are turned back upon themselves along the dot dash lines 54 and 56 to form side hems corresponding to the side hems 36 and 38 of the pocket element 10. The top edges of the reinforced element 12 are also folded back upon themselves along the dot dash lines 58 and 60 to form a tapered top hem 62 (Figs. 3 and 5).

The reinforcing element 12 is now placed upon the upper end of the pocket element 10 in such manner that the tapered upper edges of the two elements lie in the same planes. The elements 10 and 12 are so positioned that the in-turned edges of one element are in contact with the in-turned edges of the other element and the hem portions of the two elements are secured together by parallel rows of stitching 64 and 66, as is clearly shown in Figs. 3 and 5. The buttonhole 68 is then formed in the reinforced upper end of the pocket element 10.

The reinforced pocket element is then placed in an upside-down position on the shirt front 40 and with the reinforcement out. The reinforced pocket element is then secured to the shirt front by parallel rows of stitching 70 and 72 (Fig. 5), which are adjacent to and parallel with the edge 20 of the pocket element. The reinforced pocket element is then folded back upon itself along the dot and dash line 74 and the side edges of the reinforced pocket element are secured to the shirt front by parallel rows of stitching 76 and 78, 80 and 82. The button 84 is next secured 50 to the shirt front and the pocket is complete.

When the pocket is empty it lies flat against the shirt front and presents a neat and smooth appearance. The position of the lower end of the pocket under these conditions is clearly indicated in Fig. 5. This figure, however, shows

the upper end of the pocket as being unbuttoned, whereas the upper end of the pocket will normally be buttoned regardless of whether the pocket is filled or empty.

Our novel cigarette pocket is designed to carry, in a neat and convenient manner, a standard package of cigarettes and in Figs. 1 to 4, inclusive, we have illustrated our pocket as containing a cigarette package 86. Figs. 3 and 4 in particular illustrate the neat and convenient manner in which our pocket accommodates itself to the cigarette package and supports this package without tending to crush or damage the package or its contents. In Fig. 4, one corner of the upper end of the package is illustrated as being torn away to facilitate removal of the cigarettes therefrom.

An important feature of our invention resides in the arrangement whereby one or more cigarettes may be easily withdrawn from the cigarette package without unbuttoning the tapered upper end or flap part of the pocket. In order to remove a cigarette it is only necessary to push upwardly on the bottom of the pocket, as indicated in Fig. 2, until the upper end of the cigarette package is immediately below the button 84. The fingers of the other hand can then readily remove one or more of the cigarettes from the package, as clearly shown in this figure.

The removal of the entire package of cigarettes from our new and improved pocket is also easily effected. After unbuttoning the flap, the finger of one hand is placed against the bottom of the pocket and the entire package is urged upwardly so that the fingers of the other hand may grasp the upper edges of the cigarette package as they protrude beyond the lower edges of the tapered flap. The cigarette package may then be entirely withdrawn from the pocket.

From the foregoing description it will be seen that we have provided an easily constructed, unitary cigarette pocket which can be fabricated from a minimum amount of material and which

has many advantages heretofore available only in pockets made by a more expensive method and with a considerably greater expenditure of cloth.

5 While we have described our invention in connection with a preferred embodiment thereof, it will be apparent to those skilled in the art that numerous variations and modifications may be made from the structure disclosed without departing from the underlying principles of our invention. We, therefore, wish to include within the scope of the following claim all constructions by which substantially the results of our invention may be obtained by substantially the same or equivalent means.

Having illustrated and explained an embodiment of our invention, what we claim and desire to secure by United States Letters Patent is as follows:

20 In combination with a shirt of the class described having a piece of material forming the front thereof, a second piece of material secured to the shirt front and cooperating therewith to form a pocket adapted to hold a package of cigarettes and like articles, said second piece of material having an overhanging bottom secured at its upper edge to said first-mentioned piece in a horizontal plane remote from the upper end of said pocket, said second-mentioned piece of material having sides stitched throughout their length to said first-mentioned piece of material, said stitched sides extending downwardly to a horizontal plane substantially below said first-mentioned horizontal plane, said second piece of material having a tapered upper end provided with a central apex, and means for detachably securing said tapered upper end to said first piece of material to form a closed pocket for preventing accidental dislodgment of any contents 30 35 40 therefrom.

ALBERT T. BARD.
ALVIN J. WENZEL.
